ATTORNEY.

UNITED STATES PATENT OFFICE.

JOHN T. SCHAFER, OF ROCHESTER, NEW YORK.

CAR-BUFFER.

SPECIFICATION forming part of Letters Patent No. 278,606, dated May 29, 1883.

Application filed March 30, 1883. (No model.)

To all whom it may concern:

Be it known that I, JOHN T. SCHAFER, a citizen of the United States, residing at Rochester, in the county of Monroe and State of New York, have invented certain new and useful Improvements in Buffers; and I do hereby declare the following to be a full, clear, and exact description of the invention, such as will enable others skilled in the art to which it applies to make and use the same.

The object of my invention is the improvement of railways-buffers; and it consists in the employment, in combination with a buffer-rod and disk, of a hydraulic and pneumatic chamber, a piston and a spring arranged on each side of the piston, by means of which is produced an effective resistance to the colliding contact of the cars and to the shock in starting them or in increasing their speed. It is illustrated in the accompanying drawings, in which—

Figure 1 is a side elevation, partly in section, of my improvement attached to the car-frame; and Fig. 2, a horizontal view in section.

In the drawings, A represents the draw-head and buffer, of the usual form; B, a draw-bar, as well as piston-rod; C, the piston, and D the cylinder within which the piston is arranged to move, as hereinafter described.

The cylinder is composed of two pieces of cast-iron, d and d', the former being called, for convenience, the "body" of the cylinder, and the latter part the "cylinder-cap," bolted together by L-headed screw-bolts d². It is secured to the timbers on the under side of the car by means of straps (shown in dotted lines) and bolts d³, as shown in Fig. 1. V is a lug cast on the head and cylinder-cap to prevent the strap from slipping lengthwise along the cylinder. The body of the cylinder d' is formed with a flange, e', by which the same is secured by bolts to the timber e, running lengthwise of the car.

The piston-rod B, at its outer end, is screw-threaded to receive the buffer-disk; or the disk may be keyed thereto. A portion of the rod B, near the buffer-head, is turned out, as shown at b, to accommodate a bracket or support, f, in which the piston-rod has an endwise movement, the distance between the shoulders of the cut out portion being at least the same

distance as between the piston in its central position in the cylinder and the shoulders of the cylinder-head. The piston-rod B passes into the cylinder through the stuffing-box G, 55 the latter being of the usual construction, having a candle-wick filling, covered by a ring, h.

The piston C is formed to slide closely within the cylinder, and in its normal position is held about the center of the cylinder by the action 60 of the springs E and E'. The spring E is coiled loosely about the rod B, and the spring E' is connected to one end of the cylinder by a J-shaped screw, while its opposite end bears loosely against the piston-head. The piston-head has formed in its face an annular concave recess, c', which gives to the cylinder increased space for the pressure of the air and liquid cushions against the piston-head.

i' i² i³ are passages through the piston-head 70 to admit air and fluid from one side of the piston to the opposite side, and one of these passages, i³, is cut through the head of the piston-rod.

K is a gasket or packing, composed of rubber or plumbago, and which is placed in a dovetailed groove formed in the piston-head. On each side of the gasket is formed small creases l l, through which oil is forced for the purpose of lubricating the sides of the cylinder and top of the piston-head.

M is a pin inserted through a portion of the piston-head and into the rod B to hold the head more securely to the rod after it is riveted thereto.

The cylinder is provided on its upper side with passages n n', to admit the outer air within the cylinder and to opposite sides of the piston-head. The interior walls of the cylinder are cored out at each corner, as shown, to form 90 recesses, wherein are collected the gummed oil and dirt which accumulate within the cylinder, and which, if not thus collected, would cause cutting and wearing of the cylinder and piston-head.

O is a rubber gasket resting in a groove in the cylinder-body d at its junction with the cap d' to render the cylinder air-tight at that point. The placing of this gasket at the point named does away with the necessity of turning a groove in the body d, and an opposite annular flange in the cap d'.

P is an oil-hole formed in the cap d' of the cylinder to admit of the introduction of oil or other fluids therein.

After charging the cylinder with a sufficient quantity of liquid to act as a cushion, but without enough to exclude a cushion of air on each side of the piston above the fluid, the operation of the apparatus is as follows: The piston stands normally, as already stated, at about the center of the cylinder. On the colliding of the cars the piston-rod B is forced back, carrying the piston-head against the spring E' and compressing the air and liquid on that side of the piston. When the piston-head is thus forced back external air is drawn into the cylinder through one of the passages n, while the air in the cylinder on the opposite side of the piston-head is gradually forced out through the opposite passage, n'. At the same time some fluid and air in the front of the piston-head is forced back through the passages i' i² i³ to the opposite side of the piston. As the piston-head also is thus forced back or forward of the passages n', an additional suction force is produced by means of the annular recess e', which increases the distance of the air or gas and liquid cushions, thus aiding to resist and retard the shock. On starting a train or car the pressure is against the front spring, E, while the compression and operation of the air and liquid are the same as before.

My invention is applicable also to street-cars, ships, steamboats, wharves, or wherever shock is to be resisted or overcome by the meeting or sudden starting of similar large and heavy objects.

I am aware that confined bodies of air and other compressible fluids have heretofore been employed to take up the shock produced by the

colliding of cars; also, that air-cushions have 40 been employed in connection with a draw-bar to relieve the shock in starting a train; but

What I claim, and desire to secure by Letters Patent, is—

1. In a buffer, the combination of the hydraulic and pneumatic cylinder, provided with 45 passages for the admission of the outer air, the piston and the piston-rod, whereby both air and liquid are at the same time utilized as cushions both in colliding and in pulling, substantially as described.

2. The combination of the cylinder, the piston, the piston-rod, and the springs, the said 55 springs arranged within the cylinder and one on each side of the piston to take up the shock in colliding or in pulling, and the air and liquid cushions, substantially as described.

3. In a buffer, the combination of the cylinder, the piston, the piston-rod, with a cut-out portion, such as b, and the springs on opposite 60 sides of the piston, substantially as described.

4. The cylinder provided with the passages for the admission of air and of liquid, in combination with the piston provided with the 65 passages for admission to both sides of the piston of the air and liquid, and the piston-rod, also provided with a similar passage, substantially as described.

5. The combination of the cylinder provided with the flange e', the draw-bar or piston-rod, 70 with the cut-out portion b, and the timber-supports f and e², substantially as described.

In testimony whereof I affix my signature in presence of two witnesses.

JOHN T. SCHAFER.
